THERMIONIC VALVE AMPLIFIER

Bertram Morton Hadfield, Harrow Weald, England, assignor to Automatic Electric Laboratories Inc., Chicago, Ill., a corporation of Delaware

Application October 2, 1944, Serial No. 556,879
In Great Britain December 14, 1943

9 Claims. (Cl. 179—171)

1

The present invention concerns improvements in or relating to thermionic valve amplifiers and circuits therefor.

It is an object of the present invention to provide means whereby the phase angle and amplitude responses of a thermionic amplifier at high frequencies may be substantially improved in a simple manner without affecting the nominal gain and with substantial stabilisation of the nominal gain. It is a further object that the foregoing improvements should be applicable to different specimens of valve and to the same valve during its life. A further object is to ensure that the conditions of stability against self-oscillation remain unaffected when overall negative feedback is used.

According to the invention in order to obtain a phase displacement of a valve which is substantially zero between the input and output for a large range of frequencies by means of negative feedback, impedances are provided in the cathode and anode circuits respectively having susceptances and conductances of such values that the ratio of the susceptance to conductance of the cathode impedance is substantially equal to the product of the ratio of the susceptance to conductance of the anode impedance and the ratio of the sum of the grid to cathode and cathode conductances to the grid to cathode conductance at low frequencies.

In order to obtain the optimum band width over which the resultant phase angle is substantially zero, the cathode circuit conductance is made substantially equal to the grid to cathode conductance of the valve circuit at low frequencies.

The invention is applicable to triode valves as well as to screen grid valves such as the pentode. In the case of a pentode the working grid to cathode conductance of the valve circuit becomes the mutual conductance of the valve while in the case of a triode the same phrase means the mutual conductance of the valve as reduced by the effect of the anode voltage variations.

In any thermionic amplifier it is well-known that the performance at higher frequencies is limited mainly by the unavoidable anode to earth capacitance. The latter produces a phase angle between input and output voltages at all frequencies, and its effect can only be delayed in terms of increasing frequency, by modification to the anode impedance; such as for instance, the insertion of a suitable inductance in series with the conventional anode resistance. In amplifiers

5 for very large band width operation (such as those used for television), even this remedy is insufficient, and the basic time constant of the anode circuit must be reduced by using a lower anode resistance, with consequent loss of gain at lower frequencies.

In addition the presence of any series resistance negative feedback effect on each stage is detrimental, for a given stage gain, since the anode resistance must be increased, and with it the time constant.

10 By means of the invention the stage gain may be retained even with series resistance negative feedback for such stage without introducing an additional phase angle due to the increased anode time constant and in fact with a much better phase angle characteristic. Improvement is also obtained as regards constancy of amplitude response with frequency.

15 The invention will be better understood by referring to the accompanying drawings in which:

Fig. 1 illustrates in diagrammatic form the general principles of the invention.

20 Figs. 2, 3 and 4 illustrate examples of applying the invention to a pentode.

Fig. 5 illustrates the application of the invention to a multi-stage amplifier.

25 Fig. 6 illustrates a graph showing the relation of phase angle and amplitude response with frequency under different conditions.

30 Referring to Fig. 1, let V_1 be a pentode or tetrode valve, with anode and cathode admittances A_a and A_c . Let the supply busbars be as shown marked plus and minus, let the screen be taken for convenience to the positive busbar, and let the anode output voltage V be obtained from an input e . Using the normal differential valve parameter g for the mutual conductance between grid and cathode, or, in other words, the rate of change of current in the cathode circuit with respect to a change in grid voltage which should be distinguished from the more commonly spoken of mutual conductance between grid and anode, and assuming the anode impedance of the valve to be infinite and the anode current to be k times the cathode current (where k is a constant for the given valve) then

$$50 \text{ Gain} = \frac{V}{e} = \frac{k \cdot g \cdot A_c}{A_a (g + A_c)} \quad (1)$$

If A_a and A_c be expressed conventionally as $G_a + j \cdot S_a$ and $G_c + j \cdot S_c$ respectively, where G_a , G_c are the conductances and S_a , S_c are the

susceptances of the anode and cathode circuits, then

$$\begin{aligned} \text{Gain} &= \frac{k.g(Gc+j.Sc)}{(Ga+j.Sa)(g+Gc+j.Sc)} \\ &= \frac{k.g.Gc}{Ga(g+Gc)} \cdot \frac{\left(1+j\frac{Sc}{Gc}\right)}{\left(1+j\frac{Sa}{Ga}\right)\left(1+j\frac{Sc}{g+Gc}\right)} \end{aligned} \quad (2)$$

In this expression, let

$$P = \frac{k.g.Gc}{Ga(g+Gc)} \quad (3)$$

then P is the nominal gain (since it consists of a real number) and the remainder gives the phase angle ϕ as follows:

$$\phi = \tan^{-1} \frac{Sc}{Gc} - \tan^{-1} \frac{Sa}{Ga} - \tan^{-1} \frac{Sc}{g+Gc} \quad (4)$$

Now in a conventional stage, the cathode admittance is either infinite (i. e. Gc infinite, for instance, or is finite and real (i. e. Sc is zero). In the first case θ becomes

$$-\tan^{-1} \frac{Sa}{Ga}$$

or, substituting from (3)

$$-\tan^{-1} \frac{Sa.P}{k.g}$$

Therefore the phase angle is a constant for given values of Sa , P , k and g , and cannot be reduced for a given value and gain except by reducing Sa . In the second case, ϕ becomes

$$-\tan^{-1} \frac{Sa.P}{k.g} \left(1 + \frac{g}{Gc}\right)$$

for which the same comments apply, with the addition that the angle is always greater when Gc is finite.

If Gc be finite and Sc be not zero, however, it is obvious from inspection of Equation 4 that the angle may be reduced. Furthermore and owing to the fact that $\tan^{-1}\theta$ tends to θ radians when the angle is small, the net phase angle can be made sensibly zero at lower frequencies, by making

$$\frac{Sc}{Gc} = \frac{Sa}{Ga} + \frac{Sc}{g+Gc} \quad \text{or} \quad \frac{Sc}{Gc} = \frac{Sa}{Ga} \left(1 + \frac{Gc}{g}\right) \quad (5)$$

Thus, by applying Equation 5, and despite the increase in anode resistance necessitated by the finite value of Gc in order to maintain the former nominal gain, the resultant phase angle may be made zero over a substantial frequency range, while the ultimate phase angle at infinite frequency remains unaltered. The latter statement can be seen from Equation 4, since the expressions for all three component angles tend to infinity at infinite frequency, and the net result must be minus infinity, which is the same result as for a conventional stage.

The frequency band over which the phase angle remains sensibly zero by application of Equation 5, for a given gain, has an optimum value determined by the conditions which make the individual angles of Equation 4 a minimum. This is best seen by substituting (5) in (4), and also substituting for Ga in term of P from (3), as follows:

$$\begin{aligned} \phi &= \tan^{-1} \frac{Sa.P}{k.g} \frac{(g+Gc)^2}{g.Gc} - \tan^{-1} \frac{Sa.P}{k.g} \left(\frac{g+Gc}{Gc}\right) - \\ &\quad \tan^{-1} \frac{Sa.P}{k.g} \left(\frac{g+Gc}{g}\right) \end{aligned} \quad (6)$$

For given, finite, values of the variables, it is ob-

vious that the first term is the largest. Hence the conditions giving a minimum for this term, must also give the optimum zero phase angle frequency bandwidth. For given values of Sa , P , k and g , it follows, by differentiation, that this term is a minimum when $Gc=g$.

Hence by introducing a cathode conductance (Gc) equal to the grid to cathode mutual conductance (g) of the valve, an optimum frequency bandwidth is obtained over which the phase angle is sensibly zero, for a given gain, while the ultimate phase angle at infinite frequency remains unaltered. Also since the nominal gain expression (Equation 3) is only multiplied by the constant

$$\frac{Gc}{g+Gc}$$

its frequency characteristic will remain as before, while the resultant amplitude response taking into account the phase angle term of Equation 2 must be borne constant since the phase angle itself has been reduced to zero. Again, and for the reason that the phase angle degenerates ultimately to its normal value, it follows that the ultimate amplitude response must also degenerate to its normal value, i. e. zero at infinite frequency. Therefore the problems of self-oscillation in a multi-stage amplifier using overall negative feedback with stages arranged according to the invention, are not increased, and may in fact be improved if advantage be taken of the individual feedback per stage to reduce the normal value of overall feedback.

With the above optimum condition, the phase angle is

$$\phi = \tan^{-1} \frac{Sa.P}{k.g} - 2 \tan^{-1} \frac{Sa.g}{k.g} \quad (7)$$

and as regards the bandwidth for which the phase angle is sensibly zero, it can be seen that for a value of

$$\frac{Sa.P}{k.g} = 0.06$$

45 ϕ is -0.1° compared with -3.5° for the conventional stage where Gc is infinity. For an equal phase angle of -0.1° in the latter case

$$\frac{Sa.P}{k.g}$$

50 must be 0.003, i. e. a bandwidth gain of 20:1. For a moderate angle such as 1° , the respective values of

$$\frac{Sa.P}{k.g}$$

55 are 0.106 and 0.017, i. e. a bandwidth gain of 6:1. By re-writing Equation 6 as follows:

$$\begin{aligned} 60 \phi &= \tan^{-1} \frac{Sa.P}{k.g} \left(1 + \frac{g}{Gc}\right) \left(\frac{1+Gc}{g}\right) - \\ &\quad \tan^{-1} \frac{Sa.P}{k.g} \left(\frac{1+g}{Gc}\right) - \tan^{-1} \frac{Sa.P}{k.g} \left(1 + \frac{Gc}{g}\right) \end{aligned} \quad (8)$$

it can be seen that reciprocal ratios of Gc and g will give identical answers. In this manner it can be shown that the value of

$$\frac{Sa.P}{k.g}$$

70 varies only from 0.106 to 0.09 (i. e. 15%) for changes in the ratio of Gc to g from 3 to 0.3 and for a 1 degree phase angle for instance. Thus there is in fact a wide tolerance permissible in practice in the application of the invention provided the tolerance is taken about the o-

timum ratio of unity. Furthermore it is evident that changes in g with life of, or, between specimens of, the valve, will not produce material changes in the improved phase angle characteristic; and by virtue of the negative feedback effect due to the presence of Gc in the nominal gain Equation 3, it also follows that variations in gain due to the same cause will be reduced in the well-known manner.

As regards the form of the phase angle characteristic at frequencies where it cannot be assumed that $\tan^{-1}\theta=0$ radians it is obvious from Equations 6 or 8 that the first term will always give the earliest departure from this assumption. As $\tan^{-1}\theta$ is always less than θ radians in these conditions, it follows that the second and third terms will then predominate, and the angle must always tend towards a negative value. This is still true even if

$$\frac{Sc}{Gc}$$

is made greater than

$$\frac{Sa}{Ga} \left(1 + \frac{Gc}{g} \right)$$

and the only effect of such departure from Equation 5 will be to give a positive phase angle initially, increasing with frequency, followed by a subsequent changeover to a negative angle. It is possible to use such a characteristic if further delay in the onset of negative angles is required, although the degree of increase in bandwidth is not great, owing to the rapid degeneration of the characteristic to the normal type.

Having established a theoretical basis for the invention so as to form a guide to the best practical conditions of application, various embodiments employing it will be described, together with illustrations of the specific improvements in the characteristics. From Equation 5 it is clear that the most likely form of cathode circuit to employ is one of similar form to the anode circuit, otherwise the equality will only hold over a more limited frequency range, and this will be the form described. However, this is not to exclude the use of different forms of anode and cathode circuit in the application of the invention, whose usefulness lies in the application of Equation 5 and a value for Gc at around the g of the valve.

Fig. 2 shows the simplest application, in which Ca is the total anode capacitance, Ra the anode load resistance, Rc the cathode resistance and Cc the cathode capacitance. Hence

$$G_a = \frac{1}{Ra}; Sa = w \cdot Ca, Gc = \frac{1}{Rc}, \text{ and } Sc = w \cdot Cc$$

where w is the frequency in radians per second of the applied input e . The common factor

$$\frac{Sa \cdot P}{k \cdot g}$$

now becomes

$$\frac{w \cdot Ca \cdot P}{k \cdot g}$$

which may be put as

$$\frac{w}{w_0} \left(\text{where } w_0 = \frac{k \cdot g}{Ca \cdot P} \right)$$

and since w_0 is a constant for a given nominal Ca , k and g , it will be used as the frequency reference value in this and other specific embodiments.

Fig. 6 shows the relations between the phase angle and amplitude response with frequency, curves 1 and 3 respectively being for the conven-

tional circuit (i. e. $Gc=\infty$), and curves 2 and 4 respectively for $Gc=g$ and

$$\frac{Sc}{Gc} = \frac{Sa}{Ga} \left(1 + \frac{Gc}{g} \right)$$

the curves being for a given valve and nominal gain (i. e. Sa , P , k and g constant) in each case. It will be seen that zero phase angle is obtained over the usable frequency range and that the constancy of amplitude response also extends to a much higher frequency. Further the ultimate angle and amplitude are the same in both cases. The dotted curves 5 and 6 show the effects on the phase angle of making

$$\frac{Gc}{g} = 2$$

or 0.5 and 3 or 0.33 respectively, the results being the same for reciprocal ratios; it is seen that there is no change in the sensibly zero portion of the characteristic, since this depends only on the application of Equation 5, and but little change even thereafter. An interesting observation on the phase and amplitude characteristics of the invention, is that both amplitude and phase changes are rendered zero up to the highest possible frequency and then depart almost simultaneously. The amplitude in curves 3 and 4 degenerates to zero at infinite frequency while the phase angle degenerates to -90° in curves 1, 2, 5 and 6 at infinite frequency.

Fig. 3 shows a further stage in the application of the invention, by utilizing the principle of series inductances L_a and L_c . Properly chosen, the effect of these is to delay the departure from zero of the phase angle of both anode and cathode circuits normally due to the shunt capacitance. Hence their effect, when applied according to the invention, will be to produce a further increase in the sensibly zero range of the net phase angle characteristic, for the same nominal gain and valve. It is found that the best ratio of inductance to the product of the capacitance and square of the resistance is unity, although commercial deviations from this are permissible without ill effect. The sensibly zero phase angle bandwidth is extended by approximately 4 times beyond that of curve 2 of Fig. 6, and again both amplitude and angle degenerate to zero and -90° respectively at infinite frequency. The essential feature of the invention, namely that

$$\frac{Sc}{Gc} = \frac{Sa}{Ga} \left(1 + \frac{Gc}{g} \right)$$

and Gc approximates to g , can only be strictly applied when Gc is substantially independent of frequency, i. e. at low frequencies, but experiment has confirmed that these relationships are a sound guide to the best results at higher frequencies.

Fig. 4 shows another stage of development, in which the capacitances K_a and K_c are shunted across inductances L_a and L_c and again effect further individual improvement in the respective anode and cathode circuit phase angles. Hence a further frequency range over which both phase angle and amplitude remain constant is obtained.

In practice and for these more complicated circuits, having established the guiding design criteria as above, the best solutions are most readily found by experiment using an artificially large value of Ca and applying a rectangular waveform of convenient frequency. The best relationship around those predicted above, having thus been settled, they can be applied to the practical case

where C_a is comprised only by that of the anode and its associated components to earth. For instance, it has been found that the best value for C_c in the case of Fig. 3, is about 60% of its theoretical value, as calculated by the above method.

With these arrangements the buildup time for attainment of 95% steady state, were respectively as 1:0.57:0.3 for the conventional stage compared to Figs. 2 and 3 designed according to the invention, and where all three stages had the same valve and the same nominal gain. These figures demonstrate the advantage given by the invention to any amplifier.

In the practical application of the invention to any single stage, the following two points facilitate its use. Use of the optimum condition, where $G_c = g$, or any convenient ratio about this value such as from 3 to 0.33, means that R_c is of the same order as the mutual resistance

$$\left(\frac{l}{g}\right)$$

and so the grid bias conditions normally used are automatically satisfied, since such values of R_c will give biases around one half of the usable grid voltage between anode current cutoff and the inception of grid current. Generally speaking, therefore, the only changes needed to the conventional cathode circuit are the addition of a suitable value for C_c and any further components in series with R_c (such as L_c and K_c). As regards the addition of series components such as L_a and L_c , it is obvious that L_a will be small for the usual order of C_a (i. e. of the millihenry order) and is therefore convenient, whilst it is equally obvious that L_c will be approximately equal to L_a divided by the stage gain and so will be even more convenient to apply without affecting the bias conditions.

In order to maintain the nominal gain, by comparison with a conventional stage, it is necessary to increase R_a for the R_c used, according to Equation 3. Although this effect has been fully accounted for in the previous discussion of the frequency characteristics, it may cause a partial redesign in order to satisfy the steady anode voltage requirements. If, for instance, a conventional stage using the maximum permissible R_a is to be modified, it follows that increase of R_a alone will cause anode overloading by virtue of the decreased anode to negative busbar steady voltage. However, this can be avoided by redesign of the steady voltage conditions so that a smaller anode current is taken, for instance by using a lower value of screen voltage. Alternatively, and where suitable frequencies are involved, R_a may be shunted by a choke.

In many cases however, R_a is not at its maximum value permitted by the steady voltage conditions, because of the necessity to keep the anode time constant small, such as in television amplifiers. In these cases it is highly probable that R_a may be increased at least to twice its value, thus permitting the immediate application of the invention in its optimum stage of $G_c = g$.

As regards the application of the invention to a multi-stage amplifier, Fig. 5 demonstrates a typical setup. Valves V_1 , V_2 to V_n have anode and cathode admittances A_{a1} , A_{a2} , to A_{an} , and A_{c1} , A_{c2} , to A_{cn} , in accordance with the invention, and are coupled in cascade by any well-known means such as grid condensers and resistances C_2 , R_2 , C_3 , R_3 , to C_n , R_n , as shown. Provision has also been shown for overall negative

feedback of conventional type into the cathode circuit of V_1 via R_{fc} , or the grid circuit of V_1 via R_{fg} , according to the phase of the output voltage to the input, and via the feedback admittance A_f and the coupling condenser C_f . In the case of use of R_{fc} , decoupling means R_d and C_d have been shown so that no additional local feedback on V_1 can be given by the voltage on R_{fc} . The input is applied between terminals 1, 2, and the output is taken from the anode circuit of V_n , via terminal 0 and one of the supply busbars marked plus and minus. As mentioned before, the degree of overall feedback may be reduced at least by the local amount given by A_{c1} , A_{c2} , etc., on each stage, and also on account of the improved phase angle and amplitude characteristics of each stage, so that the care necessary to prevent self-oscillation as high frequencies need not be so great as normally.

While the case of the pentode or tetrode valve has been taken as being the simplest to demonstrate the invention and as being the type of valve most likely to be used in practice, the methods shown and described can be applied to other valve types. Generally speaking, however, the application is less efficient if the anode potential variations affect the cathode current or grid potential. Again it is not essential to the invention that the steady electrode voltages shall be related in any specific manner (such as has been shown for the screen and anode voltage supplies), since the functions and derivation of the invention are concerned with the differential operation of the valve and its associated circuits.

35 I claim:

1. In a wide band amplifier, a thermionic valve having at least a cathode, a grid, and an anode, an input circuit coupled to said grid, an output circuit coupled to said anode, and impedances 40 in the anode and cathode circuits of values such that the ratio of susceptance to conductance of the impedance in the cathode circuit is substantially equal to the ratio of the susceptance to conductance of the impedance in the anode circuit times the sum of the grid to cathode conductance and the conductance of the impedance in the cathode circuit, divided by the grid to cathode conductance, whereby substantially zero phase displacement between signal waves in the 45 input and output circuits is obtained over a wide frequency range.

2. A wide band amplifier as claimed in claim 1 wherein the conductance of the impedance in the cathode circuit is made substantially equal to the grid to cathode conductance of the valve 55 in order to obtain the optimum bandwidth over which the phase displacement is substantially zero.

3. In a wide band amplifier, a plurality of thermionic valves each having at least a cathode, grid, and an anode, said valves connected in cascade, an input circuit coupled to the grid of the first valve and an output circuit coupled to the anode of the last valve, and impedances in the anode and cathode circuits of said valves having values such that the ratios of susceptance to conductance of the impedances in the cathode circuits are substantially equal to the ratios of the susceptance to conductance of the corresponding impedances in the anode circuits times the sum of the grid to cathode conductance and the conductance of the impedance in the cathode circuit divided by the grid to cathode conductance of the corresponding valves, whereby substantially zero phase shift between the input and out-

signal waves is obtained over the major portion of the operating range.

4. A wide band amplifier as claimed in claim 1 wherein the conductance of the impedance in the cathode circuit lies between one-third and three times the grid to cathode conductance of the valve.

5. A wide band amplifier as claimed in claim 1 wherein the impedances in the anode and cathode circuits each comprise a resistor shunted by a condenser.

6. A wide band amplifier as claimed in claim 1 wherein the impedances in the anode and cathode circuits each comprise a resistor and inductor in series shunted by a condenser.

7. A wide band amplifier as claimed in claim 1 wherein the impedances in the anode and cathode circuits each comprise a resistor and inductor in series shunted by a condenser of values such that the inductance equals the product of the capacitance and the square of the resistance.

8. A wide band amplifier as claimed in claim 1 wherein the impedances in the anode and cathode circuits each comprise an inductor in series with a resistor, a first condenser in shunt of the inductor, and a second condenser in shunt of the series combination.

9. In a wide band amplifier, a thermionic valve having at least a cathode, a grid, and an anode, an input circuit coupled to said grid, an output circuit coupled to said anode, similar complex impedances connected in the anode and cathode circuits of said valve, the ratio of the susceptance to conductance of the cathode impedance being approximately twice the ratio of the susceptance to conductance of the anode impedance, whereby a sensibly zero phase displacement between signal waves is obtained in the input and output circuits over a wide frequency range.
